MAKING OF RAYON

Earle J. Richard Beattey, Edgewood, R. I.

Application May 26, 1933, Serial No. 672,972

2 Claims. (Cl. 18—8)

This invention relates to the production of a thread composed largely of rayon filaments, and has for one of its objects the provision of a thread which, when woven into a fabric, will not remain creased in such a manner as occurs in all rayon garments today.

Another object of the invention is to treat, in a mechanical manner as distinguished from a chemical manner, rayon filaments in order that the desired non-creasing result may be obtained.

Another object of the invention is to so relate the rayon filaments of a thread that they will give support one to the other that their combined elasticity may be brought into play for causing these threads to resume a normal uncreased condition when woven into fabric so that if a rayon fabric becomes wrinkled upon hanging the same up, the wrinkles will come out of the fabric in the same manner that they come out of fabrics made of animal fibers such as wool and natural silk.

Another object of the invention is to support the rayon filaments by a thread or core of a different material in order that the composite thread may be straightened as to its elastic qualities and be better suited for the production of woven fabrics and garments therefrom.

A further object of the invention is the provision of a supporting core for a composite thread and the forcing of the rayon filaments toward this core and into close contact therewith that these rayon filaments may be better supported and a composite thread provided having more desirable qualities for weaving into fabrics and formation of garments therefrom.

With these and other objects in view, the invention consists of certain novel features of construction, as will be more fully described, and particularly pointed out in the appended claims.

40 In the accompanying drawing:

Fig. 1 is a side elevation partly in section and largely diagrammatic of the layout of a machine for forming rayon filaments with my invention shown therein.

45 Fig. 2 is a sectional view through the spinneret and also diagrammatically showing my improved member in section for condensing the plurality of rayon filaments extruded through the spinneret.

50 Fig. 3 is a view similar to Fig. 2 illustrating a core as extending through the spinneret and as formed in the composite thread.

Fig. 4 is a diagrammatic view illustrating a cross-section of filaments as they would appear

55 when my condensing device is not used.

In the use of rayon, which is a cellulose product usually formed by the viscose process using wood pulp as the supply of cellulose, when formed into a garment it is found that the garment becomes creased through wear and whereas, when a garment is made of silk or wool the hanging of the same upon a form or suitable support usually causes these wrinkles or creases to come out of the garment that, with the use of rayon these creases remain set to a far greater extent and will not disappear from the garment under such similar treatment, and I have attributed this to the air spaces present in any rayon thread between the filaments thereof which occur to a far greater extent in a rayon thread than they do in a silk thread, and I find that by manipulating the filaments of these rayon threads by twisting or the like after formed I do not materially reduce this air space to any effective extent as the filaments seem to be set in a certain spaced relation after they emerge from the coagulating bath and attain their finished or formed state. This possibly may be by reason of the fact that the coagulating baths which contain other sulphate salts as well as sulphuric acid cause the indentation of these filaments and an irregular formation and thus provide a multiplicity of air pockets. Further the individual rayon filaments possess but a relatively small amount of elasticity and thus in this spaced relation they cannot support themselves against creasings of a fabric when they are woven into this form and the fabric formed into a garment, and in order that this effect may be minimized to a material extent I have provided a means for forcing the fibers close together before they become set and while in a rather gelatinous state in the coagulating bath which, at this time, permits of their being molded or set closer together, and the air spaces about the fibers reduced so that as they emerge from the coagulating bath they are in an assembled and supported condition to better assist each other in the elasticity which they have and resist the strains of folding or creasing to a far better extent, and in order that this property may be further enhanced I may insert a core of thread formed of fibers of an animal nature such as silk or wool, or even fibers of any supporting material that the desired properties minimizing creasing, when the thread is formed in a fabric, may be had, and the following is a detailed description of the present embodiment of this invention illustrating the preferred means by which these advantageous results may be accomplished.

With reference to the drawing I have illus-

trated in Fig. 1 a portion of an apparatus which is used more generally in the viscose process of providing rayon. This apparatus consists of a tank 10 having a coagulating bath 11 therein which contains largely sulphuric acid although it usually contains other sulphate or sulphite salts which are found of advantage in providing the desired coagulating effect upon the viscose or exuded cellulose mixture which has been properly aged in an accustomed manner.

This cellulose mixture is forced by a suitable pump in the usual manner through the candle filter 12 thence through the glass tube 13 and outwardly through a spinneret or nozzle 14 usually formed of the noble metals to prevent corrosion and also to permit cleaning by burning out. This nozzle is held in place by a coupling 15 having an inwardly extending flange 16 threadingly engaging the collar member 17 along the threads 18 to hold the same in engagement with the glass tube through the packing 19 as illustrated in Fig. 2. This spinneret is provided with a multiplicity of openings 20 through which the cellulose mixture or viscose 21 is forced into the coagulating bath 11 and thence is carried up through the guide 22 over a pulley 23 and into a flaring portion 24 of the traverse tube 25 reciprocated by mechanism 26 to be deposited in a centrifuge 27 in the form of an annular or hollow cylindrical cake which centrifuge is rapidly rotated through suitable shaft 28.

The coagulating bath, particularly when containing the sulphate salts, as above mentioned, will cause the filaments of rayon to assume shapes different than the shape of the holes in the spinneret, which are truly circular, and the shapes in cross-section will approximate that shown in Fig. 4, there being a drawing in along certain portions of the surface of the filament and a general distortion which varies with different baths and different sorts of cellulose used, and also varies with different processes used, but in each of these different cases these filaments are spaced apart largely and air spaces occur between them, and in order that these may be brought closer together while the filaments are in a gelatinous state and not fully set in the coagulating bath I have positioned a tapered guide member 30 in the bath 11 at a point between the spinneret and the surface 40 of the bath and usually closely adjacent the spinneret and at a point where the filaments are in a still soft or formable state so that the filaments will pass through this guide member which is tapered having a mouth portion 31 and a discharge opening 32, the discharge opening being much smaller than the entrance mouth and the

walls being formed frustro-conical as shown at 33 connecting these entrance and discharge openings so as to compress the filaments, and bring them closer together than the openings in the spinneret, as drawn therethrough on their way from the spinneret to their point of exit from the coagulating bath. By this arrangement these filaments will be crowded closely together to better support each other and provide a unified elasticity which will assist them in returning to their own desired straight shape when present in a fabric which has been creased or folded.

In order that this elastic action may also be enhanced I may choose to insert a core 34 of some different material such possibly as a natural silk, 15 wool, cotton or such thread by any known method. This thread or core extends through the tube 13 and through the spinneret 14 having a central opening 35 provided therefor and will move along at the same rate as the material is 20 extruded about this core and will be pressed into firm contact therewith by my tubular guide 30. Also a thin film of rayon may be formed as a coating about the core. By this arrangement a composite thread is provided which will have the combined elasticity of the different elements crowded one in close contact with the other and into contact with the core of different material and will be better for knitting or fabrics where sharp bends occur.

The foregoing description is directed towards the method and construction illustrated, but I desire it to be understood that I reserve the privilege of resorting to all the equivalent changes to which the construction and method are susceptible, the invention being defined and limited only by the terms of the appended claims.

I claim:

1. In an apparatus for making rayon, a coagulating bath, a spinneret therein, and a member 40 having entrance and discharge openings of different size with which said filaments contact and through which said filaments pass, said discharge opening being smaller and of a size less than the combined diameter of the rayon filaments after 45 their extrusion from said spinneret.

2. In an apparatus for making rayon, a coagulating bath, a spinneret therein, and a member having entrance and discharge openings of different size connected by a gradually decreasing 50 bore with which said filaments contact and through which said filaments pass, said discharge opening being smaller and of a size less than the diameter of the rayon filaments after their extrusion from said spinneret.

EARLE J. RICHARD BEATTLEY.
